INVENTOR,

August D'Huyvetters,
John Stevans.

ATTORNEY.

UNITED STATES PATENT OFFICE.

AUGUST D'HUYVETTERS, OF PATERSON, NEW JERSEY.

WEFT-STOP-MOTION MECHANISM FOR LOOMS.

1,199,354.

Specification of Letters Patent. Patented Sept. 26, 1916.

Application filed November 12, 1915. Serial No. 61,006.

To all whom it may concern:

Be it known that I, AUGUST D'HUYVETTERS, a citizen of the United States, residing at Paterson, in the county of Passaic and State of New Jersey, have invented certain new and useful Improvements in Weft-Stop-Motion Mechanisms for Looms, of which the following is a specification.

This invention consists in certain improvements in weft stop motions for looms of the class set forth in my U. S. Letters Patent No. 755,464 and has for its object to insure the stopping of the loom on each and every instance of failure of weft and in general to increase the efficiency of the mechanism.

In the accompanying drawing, Figure 1 is a plan view of the invention; Fig. 2 is a sectional view, looking toward the left in Fig. 1; Figs. 3 and 4 are sectional views on the lines $x-x$ and $y-y$ of Fig. 6; Fig. 5 is a front elevation of a certain guide bracket; and, Fig. 6 is a front elevation of the batten and so much of the stopping mechanism as is attached thereto.

a is that part of the loom frame which forms the breast beam, on which at b is pivoted the lever c which is adapted when moved to release the controller d , normally holding the power on the loom, from the notch e of the bracket f so that said controller will throw off the power.

Sliding in the brackets g and h attached to the batten a' is the member i in the form of a bar having to the right of the bracket g a concave shoulder j adjoined by the inclined surface or cam-way k , which rises somewhat above the shoulder. The member i has at its left hand end a set screw l which, when the same is held opposite the lever c , is adapted as the batten beats up to engage and so move said lever to trip the controller e .

Member i is normally held to the right, in a position where the set-screw l will not engage lever c , by spring m connecting it with the batten. It is drawn to the left, to a limit where said set-screw will be more or less to the left of lever c , by the strap n connecting said member with the breast beam and preferably extending through bracket h around a roller thereon.

As the member i reciprocates, due to the alternately acting influences of the strap and spring its cam-way k impinges against the turned-off curved end or arm p of a rod q arranged to oscillate in the bracket g and

forming the axial part of a catch device including the weft-fork r which plays up and down in the usual manner in a recess s in the top of the batten. Arm p of rod q is normally held depressed by gravity acting thereon and on a wire t which is freely pivoted at u to the batten and penetrates loosely a hole v in the arm.

The cam-way k and arm p present to each other convex surfaces (Figs. 3 and 6). The operation, modified as hereinafter stated by the said convex surfaces of the cam-way k and arm p and by the weight afforded by wire t , is substantially the same as in my aforesaid patented mechanism. That is to say, each time the batten beats up the member i is drawn to its right-hand limit so that the set-screw l clears lever c , provided, however, there is no failure of weft, and each time the batten moves back said member is drawn to the left, its cam-way k elevating arm p and so raising the weft-fork for the passage of the shuttle. Should there be a failure of filling, the catch device including the fork r and shaft q will be free to wipe down the incline k until shoulder j is encountered, so that member i will be locked in the position where the set-screw l will be opposite and so engage lever c .

By forming the co-engaging surfaces of arm p and member i convex and by employing the weight t to exert an always constant downward pressure on the catch device and steady the action thereof the efficiency of the mechanism, especially in respect to effecting the stopping of the loom without fail in every instance of failure of weft, is greatly increased; the convex surfaces result in a movement of the catch device that is quick at first but gradually slows down, it being noted that the rod forming the axial part of the catch device is arranged in a vertical plane closer to that of the bar i having the cam-surface k than the lowest part of said surface is from the horizontal plane of the rod, so that the arm p is not thrown out of contact with cam-surface k by the impact therewith but, remaining in contact therewith, is therefore certain to impinge shoulder j if only failure of weft allows the arm to remain in contact with surface k .

Having thus fully described my invention, what I claim as new and desire to secure by Letters Patent is:—

1. A stop motion mechanism of the class described including a horizontally sliding

member having a locking shoulder and adjoining said shoulder an inclined convex cam-way, and also including a weft-controlled catch-device pivoted on a horizontal axis, the axial part of said device being a rocking rod arranged in a vertical plane closer to that of said cam-way than the lowest part of said cam-way is from the horizontal plane of the rod, said rod having one end bent off and curved, its curved part overlying and presenting its convex side to said member and being engageable by the locking shoulder and cam-way of said member.

2. In combination, the loom frame, the moving batten, control means on the frame including a movable device to be actuated, a weft-engaging catch movable on the batten

and normally held against the weft, a back-and-forth moving member arranged on the batten and normally held out of but movable into position to engage and actuate said device, means, including a connection between said member and the batten, to move the latter into said position, said member having a locking shoulder engageable by the catch for locking said member in said position and adjoining said shoulder a camportion engageable with a portion of the catch to move the same from the weft, and a gravity actuated weight pivotally attached to the batten and penetrating loosely said catch.

In testimony whereof I affix my signature.

AUGUST D'HUYVETTERS.
